by

UNITED STATES PATENT OFFICE.

ALFRED M. GRANICH, OF NEW YORK, N. Y., ASSIGNOR TO WESTERN ELECTRIC COMPANY, INCORPORATED, OF NEW YORK, N. Y., A CORPORATION OF NEW YORK.

POWER LINE SIGNALING.

Application filed April 7, 1924. Serial No. 704,380.

To all whom it may concern:

Be it known that I, ALFRED M. GRANICH, a citizen of the United States of America, residing at New York city, in the county of Bronx and State of New York, have invented certain new and useful Improvements in Power Line Signaling, of which the following is a full, clear, concise, and exact description.

10 This invention relates to power line signaling systems in which a high frequency signaling current is superimposed upon and transmitted along with the power carrying currents of the line. Particularly, it relates to the circuit and apparatus by means of which the superposition of the signaling currents upon the power currents is accomplished.

In systems of this type, it is generally the case that the power line is normally used to transmit large currents of high voltage and that the high frequency currents are small and of low voltage. The type of apparatus used for the transmission and for the reception of high frequency signal waves is not adapted to withstand the potentials of power transmission and consequently the circuits provided to superimpose these currents upon the power currents in the line must be such as to prevent the power currents traversing or their potentials being impressed upon the signal apparatus. Further, it is necessary that the users of the signaling apparatus be protected against danger of contact with high potential conductors, particularly in the event of failure of any of the elements of the superimposing circuit under the stress of the power transmission voltages.

In addition to these requirements placed upon the superimposing circuits by need for protection, other requirements arise from the necessity of efficient transmission of the signal waves between the source and the receiving apparatus. The generators of high frequency waves used for signaling are generally of limited power, and it is common practice to operate them to deliver to the line the maximum power determined only by the internal impedance of the generator. It follows then in accordance with a well known principle of electric circuits that the electric waves should, at each point in the transmission circuit, be propagated into an impedance equal to that of the part of the circuit they have left. The superimposing

circuit which connects the source of high frequency waves and the power line should therefore have an impedance that substantially matches that of the line and its various connected apparatus.

Line noises must also be excluded from the signaling apparatus, particularly if the system is used for the transmission of speech. Such noises are due to high frequency currents that practically always accompany the power currents, as, for example, the harmonics of the fundamental wave of an alternating current power system, the frequencies of which may be as high as 5000 cycles per second. Under certain conditions also there may be present high frequency currents due to the interception by the power line of radio signaling waves which may appear as interfering noises in the signal receiving apparatus. To suppress these currents without unduly restricting the frequency range available for the transmission of signals, it is desirable that the superimposing circuit possess a selective transmission characteristic that discriminates sharply against the undesirable frequencies, and at the same time permits the free transmission of a broad band of frequencies.

In accordance with this invention, these various requirements are met by using for the superimposing circuit a broad band filter of the type described in U. S. Patent No. 1,227,113, May 22, 1917, to G. A. Campbell, and embodying therein certain features directed to protection against high voltages. The filter is designed to pass high frequency waves and to attenuate not only the principal component of the power current, but also all of its harmful harmonics and associated noise producing currents. At the end connected to the power line, it is terminated with series impedances, which include condensers the effective impedance of which to the power currents is very large and in which the greater part of the power voltage is absorbed. These condensers are of a design adapted to withstand high voltages and so serve as a primary means for protecting the signaling apparatus and the user against the line voltages. The other sections of the filter serve to reduce the residual fundamental voltage and its harmonics to negligibly small intensities. The elements of these sections, being protected from the principal stress of the power line voltage, are

constructed to withstand only the smaller voltages usually associated with signal transmission.

As a further means of protection, there is inserted between the series end section and the subsequent sections a protective device comprising a spark gap and fuses which, in the event of failure of one of the terminating condensers, operates to isolate the signal apparatus from the line.

The nature of the invention will be more fully understood by reference to the following detailed description taken in connection with the appended drawing, which shows the invention as applied to the terminal apparatus of a signaling system.

In the figure, 1 is a high frequency telephone station adapted for transmitting and receiving modulated high frequency waves.

20 The transmitting apparatus comprises a telephone transmitter 2, a source 3 of high frequency waves, a modulator 4 upon which are impressed waves from sources 2 and 3, and a selective circuit 5 which is adapted to transmit the desired modulated waves. The receiving apparatus comprises a selective circuit 6 arranged to transmit incoming waves of a different frequency from the outgoing waves, a demodulator or detector 7 on which the incoming waves are impressed, and a telephone receiver 8 connected to receive the low frequency output of the demodulator. The two channels constituted by the transmitting and receiving apparatus converge

35 at points 9 and 10 and are continued in a common path through the coupling circuit which comprises two sections 11 and 12, and through disconnecting switches 23 to the bus-bars 13 of the power transmission line.

40 Section 12 of the coupling circuit comprises high voltage series condenser 14 and a shunt inductance coil 15, the winding of which is connected to ground at its mid-point. The elements of this section constitute the primary protection for the telephone apparatus

45 against the line voltages and are isolated as an additional safety measure by being mounted on a separate concrete pedestal 16 and enclosed within a metallic cage 17. The

50 condensers 14 are designed to withstand the voltage of the transmission line which in general will be greater than 5000 volts and may in particular cases exceed 100,000 volts.

55 The type of condenser preferred is one having an oil dielectric, or alternatively a composite dielectric consisting of glass plates immersed in oil, and being contained in a substantial metal case which may be grounded to prevent the accumulation thereon of

60 static charges. The shunt coil 15 ordinarily is not exposed to large voltages but should be wound with a substantial conductor to enable it to carry a heavy current for a short period in the event of a short circuit occurring in one of the condensers 14. Section 11

comprises additional series condensers 18 and shunt inductance coils 19, these elements being arranged to cooperate with the elements 14 and 15 to constitute a broad band filter in accordance with the invention of the above mentioned patent to G. A. Campbell. The particular type of filter disclosed in the drawing is of the type known as "high-pass" the band of frequencies transmitted extending from a selected cut-off frequency to infinity. Other well known types of filter may, however, be used in which a limited band of frequencies is transmitted, the feature of the series condensers and the shunt inductance coils being retained. The elements 14 and 15 of the high voltage section require careful construction and the use of a large amount of material to enable them to withstand the line voltage stresses and the current surges that may occur in the event of failure of one of the condensers. If the same construction were to be employed in the additional elements, an extremely expensive filter would result. The use of a secondary protective means 20 inserted in the circuit between the high voltage and the low voltage groups makes such expensive construction unnecessary, and with this additional protection provided the elements 18 and 19 may be constructed to withstand only the low voltages associated with the transmission of telephone currents a large saving of materials and expense being thereby effected. Device 20 includes bridging spark gaps 21 and series fuses 22, the spark gaps being adjusted to discharge at a voltage which is not great enough to damage the telephone apparatus, and the fuses being adapted to effectually isolate the apparatus in the event of a short circuit occurring in the high voltage condensers. The discharge gaps 21 may be of the open space type described in U. S. Patent No. 1,362,387 to D. T. May, December 14, 1920, the discharge voltage of which may be adjusted to as low a value as 500 volts. Discharge gaps of this type may be used in those systems in which the power line voltage is not greater than about 10,000 volts. When greater voltages are used for the power transmission more substantial discharge gaps, for example, as the well known horn-gap type, may be used. These generally are adapted to discharge at voltages larger than 500 and it is necessary that the condensers 18 have dielectric strength accordingly great.

The nature of the invention having been fully described, the novel features are set forth in the following claims.

What is claimed is:

1. In combination, a power transmission line, a signal translating system, and a broad band wave filter connected between said translating system and said power line, said filter comprising two groups of elements,

- 5 said groups being physically separated, one of said groups comprising elements adapted to low voltages of signal communication and the other of said groups including terminal 10 elements adapted to the voltages of said power line, and said other group being enclosed within a protective compartment.
2. In combination, a power transmission line, a signal translating system, and a broad band wave filter connected between said translating system and said power line, said filter comprising two groups of elements, said groups being physically separated, one of said groups comprising elements adapted 15 to low voltages of signal communication and the other of said groups including terminal condensers adapted to withstand the voltages of said power line and being enclosed within a protective compartment.
- 20 3. In combination, a power transmission line, a signal translating system, and a broad band wave filter connected between said translating system and said power line, said filter comprising two groups of elements, said groups being physically separated, one of said groups comprising elements adapted 25 to low voltages of signal communication and the other of said groups comprising two terminal condensers adapted to withstand the voltages of said power line, and an inductance coil connected therebetween and having the mid-point of its winding grounded, said coil and said condensers being enclosed within a protective compartment.
4. In combination, a power transmission line, a signal translating system, and a broad band wave filter connected between said translating system and said power line, said filter comprising two groups of elements, said groups being physically separated, one of said groups comprising elements adapted to low voltages of signal communication and the other of said groups comprising two terminal condensers adapted to withstand the voltages of said power line, and an inductance coil connected therebetween and adapted to withstand surges of current from said power line, said coil and said condensers being enclosed within a protective screen.

In witness whereof, I hereunto subscribe my name this 4th day of April A. D., 1924.

ALFRED M. GRANICH.
